United States Patent Office.

HENRY McCAN, OF HANOVER, OHIO.

Letters Patent No. 70,731, dated November 12, 1867.

IMPROVEMENT IN RAILROAD TRACK.

The Schedule referred to in these Letters Patent and making part of the same.

TO ALL WHOM IT MAY CONCERN:

Be it known that I, HENRY McCAN, of Hanover, in the county of Columbiana, and State of Ohio, have invented certain new and useful Improvements in Railroad Tracks; and I do hereby declare that the following is a full and complete description of the same, reference being had to the accompanying drawings, making a part of this specification, in which—

Figure 1 is a top view of the track.

Figure 2 is a side view.

Figure 3 is an end view.

Like letters of reference refer to like parts in the views.

The rails of this track are constructed in two sections, A B, fig. 2; A being the upper section or tread-rail, on which the wheels run, and B the lower section or base-rail, both of which are of the peculiar shape shown in fig. 3. Extending along the upper side of the base-rail is a rib, C, to which is fitted the upper rail A, by means of a corresponding groove made in the under side of the upper rail. The two rails are then fastened together by bolts *a*, and, when thus fitted and bolted, are shown in fig. 3. D is an iron tie and chair, on which the rails are placed. The ends of this tie are so constructed as to form a chair, E, by which the base-rail is secured. F are stay-bolts or braces. These bolts are provided with adjusting-nuts G, one on the inner side of each rail, and one on the outer, the purpose of which is to regulate the lateral trend of the rails, and thereby maintain their proper relative distance from each other.

The manner of laying this track is as follows: The ties C are buried in the ground, at such a depth as to include all of the base B below the stay-bolts. The base-rails are then laid on the ties, and properly secured in the chairs, the number of which being more or less, as the nature of the ground may determine. The trend of the rails, being properly adjusted by the bolts, the road is then gravelled or ballasted in the usual way. The base or ground-rails of the road, on being thus constructed, the tread-rails A are then laid upon them and bolted to the same, as above described, and shown in the drawing.

A road thus constructed dispenses with the use of the wooden cross-ties, which are ever rotting and insecure. In the road, the base-rail having a broad flat surface rests upon the ground in part, as well as upon the iron cross-ties or chairs, thereby requiring a less number of cross-ties for the support of the rail, and which, not being subjected to rapid decay, is much stronger, safer, and durable.

What I claim as my improvement, and desire to secure by Letters Patent, is—

The construction and arrangement of the base and tread-rails A B, in combination with the chairs and ties D E and adjusting-bolts F, in the manner substantially as set forth.

HENRY McCAN.
